(57) **CLAIM**

The ornamental design for a display screen with animated graphical user interface as shown and described.

DESCRIPTION

FIG. 1 is a front view of a first image of a first embodiment of display screen with animated graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a first image of a second embodiment of a display screen with animated graphical user interface; FIG. 8 is a front view of a second image thereof; FIG. 9 is a front view of a third image thereof; FIG. 10 is a front view of a fourth image thereof; FIG. 11 is a front view of a fifth image thereof; FIG. 12 is a front view of a sixth image thereof; FIG. 13 is a front view of a first image of a third embodiment of a display screen with animated graphical user interface; FIG. 14 is a front view of a second image thereof; FIG. 15 is a front view of a third image thereof; FIG. 16 is a front view of a fourth image thereof; FIG. 17 is a front view of a fifth image thereof; FIG. 18 is a front view of a sixth image thereof; FIG. 19 is a front view of a first image of a fourth embodiment of a display screen with animated graphical user interface; FIG. 20 is a front view of a second image thereof; FIG. 21 is a front view of a third image thereof; FIG. 22 is a front view of a fourth image thereof; FIG. 23 is a front view of a fifth image thereof; FIG. 24 is a front view of a sixth image thereof; FIG. 25 is a front view of a first image of a fifth embodiment of a display screen with animated graphical user interface; FIG. 26 is a front view of a second image thereof; FIG. 27 is a front view of a third image thereof; FIG. 28 is a front view of a fourth image thereof; FIG. 29 is a front view of a fifth image thereof; and, FIG. 30 is a front view of a sixth image thereof. The appearance of the animated images sequentially transitions between the images shown in FIGS. 1-6, FIGS. 7-12, FIGS. 15-21, FIGS. 13-18, FIGS. 19-24, and FIGS. 25-30, respectively. The process or period in which one image transitions to another forms no part of the claimed design.

(Continued)

The broken lines illustrate portions of the display screen and portions of the graphical user interface that form no part of the claimed design.
